Atty.

UNITED STATES PATENT OFFICE.

HENRY ALEXANDER RONGONUI REEVES, OF CHRISTCHURCH, NEW ZEALAND.

SHOE LACE.

Application filed July 13, 1928, Serial No. 292,504, and in New Zealand July 20, 1927.

This invention relates to laces for boots and shoes, the object of the invention being to obviate the tying or knotting of the lace end.

5 In lacing shoes, in order to avoid the tying or knotting of the lace where the lacing ends, it is necessary that one end of the lace should be fixed or attached to the shoe in an eyelet, and in order to so secure the end of the lace, 10 the usual cylindrical tag on the lace is sometimes bent into the shape of a hook or the tag is removed and the lace end knotted. These methods result in discomfort owing to the pressure exerted by the foot on the knot 15 or hook.

According to my invention, a shoe lace is formed with a stop at one end thereof in the shape of a disc like member, whereby the lace is prevented from being withdrawn from the 20 eyelet of a shoe or boot, the stop being so shaped that it will not cause discomfort to the wearer, when located between the shoe and the foot.

In carrying out the invention when a fabric lace is used, a flat disc like end or stop is provided, and the lace passed through an opening in the centre of the disc. The end of the lace is frayed, the frayed parts being spread outwards in a radiating direction over 30 the face of the disc, so as to extend to near the circumferential edge of such disc.

Another disc of slightly larger diameter is placed over the first disc, so that the frayed ends of the lace will lie between the two discs. 35 The two discs are then secured together so as to retain the ends of the lace firmly between them. The usual tag may be used on the other end of the lace.

The two discs may be secured in any desired 40 manner, such as being glued together by a suitable glue or clamping the edge of one disc over the edge of the other.

In the case of a leather lace the stop, preferably disc shaped is formed with a hollow stem projecting from its centre and into this 45 stem the end of the lace is placed and securely gripped therein by clamping or crimping the stem on to the lace.

The invention will be described with the 50 aid of the accompanying drawings:—

Figure 1, is a perspective view of the complete lace.

Figure 2, is a perspective view of the parts 55 forming the stop and showing how the end of the lace is attached thereto, but drawn to

a much larger scale than the lace would be used.

Figure 3, is a cross sectional elevation through the stop showing one form of securing the two discs. 60

Figure 4, is an elevation showing another form of securing the two discs together.

Figure 5, is a section through an eyelet showing how the lace is used.

Figure 6, is a cross section showing the 65 stop applied to a leather lace.

Figure 7, is a section through an eyelet showing how the form of stop illustrated in Figure 6 is used.

Referring to the drawings, the lace 1 is 70 passed through an opening 2 in a disc 3 of metal or other material. The end of the lace is frayed as shown in Figure 2 and such frayed portion 4 being spread outwards in a radiating direction over the face of the disc 75 3, so as to extend near to the edge of such disc. Another disc 5 of slightly larger diameter, is placed over the disc 3, so that the frayed ends 6 of the lace will lie between the two discs. The edge 7 of the disc 5 is then 80 clamped around the edge of the disc 3 as shown in Figure 3, thereby retaining the frayed ends of the lace firmly between the two discs.

The lace may now be placed through an 85 eyelet of a shoe or the like as indicated in Figure 5, and will not form any projection that will cause discomfort to the wearer.

Referring to Figure 4, the two discs may 90 be of the same diameter, and glued together, the glue being interspersed with the frayed ends 6, as indicated at 8 in Figure 4.

Referring to Figures 6 and 7 which show the stop applied to a leather lace, the disc 95 10 has a hollow stem 11 projecting centrally from such disc, and into this stem the end 9 of the lace is inserted and securely gripped therein by clamping or crimping the stem on to the lace as indicated in Figure 6. In this case when the lace is in position on a 100 shoe the stem 11 passes through the eyelet 12.

What I claim is:—

1. A shoe lace having one end passing through a disc, the end of such lace frayed outwards in a radiating direction so as to lie upon the face of such disc, and another disc secured over such first disc, adhesive being applied between the discs, so as to clamp the frayed ends of the lace firmly between the two discs, substantially as described. 110

2. A shoe lace having one end thereof frayed, a disc, a central opening in such disc through which the lace is passed, and another disc of slightly larger diameter than the first disc, and secured circumferentially to the edge of the first disc, adhesive being applied between the discs, whereby the frayed end of the lace is firmly held between the two discs, substantially as described.

10 3. A shoe lace having one end passing

through a disc, the end of such lace frayed outwards in a radiating direction, so as to lie upon the face of such disc, and another disc secured over such first disc, and held in position by glueing, substantially as described. 15

In testimony whereof, I have signed my name to this specification.

HENRY ALEXANDER RONGONUI REEVES
